UNITED STATES PATENT OFFICE.

GEORGE W. MOORES, OF NEW ORLEANS, LOUISIANA.

DESIGN FOR A HARNESS-ROSETTE.

SPECIFICATION forming part of Design No. 34,067, dated February 12, 1901.

Application filed January 21, 1901. Serial No. 44,229. Term of patent 7 years.

To all whom it may concern:

Be it known that I, GEORGE W. MOORES, a citizen of the United States, residing at New Orleans, in the parish of Orleans and State of Louisiana, have produced a new and original Design for a Rosette, of which the following is a specification.

This invention relates to a design for a harness-rosette, and the essential feature resides in the design as illustrated in the accompanying drawings, wherein—

Figure 1 is a perspective view of a rosette embodying the features of the design. Fig. 2 is a top plan view of the same. Fig. 3 is a transverse vertical section.

The numeral 1 designates a circular rim having depressions 2 at diametrically opposite points, and from the center of one of said depressions a truncated projection 3 verti-

cally rises. From other opposite diametrical points convex arched members 4 extend to the center and intersect above the plane of the rim, but lie wholly within the peripheral confines of the latter, the said members being flat. Between two terminals of the members 4 another truncated projection 5 rises from the rim.

Having thus described the invention, what is claimed as new is—

The design for a harness-rosette, as herein shown and described.

In testimony that I claim the foregoing as my own I have hereto affixed my signature in the presence of two witnesses.

GEO. W. MOORES.
